[57] CLAIM

The ornamental design for a cue tip tapper and shaper, as shown and described.

DESCRIPTION

FIG. 1 is a perspective view of a cue tip tapper and shaper showing my new design;

FIG. 2 is a sectional elevation taken along line 2—2 of FIG. 1;

FIG. 3 is a rear elevation thereof;

FIG. 4 is a top plan view thereof;

FIG. 5 is a front elevation thereof;

FIG. 6 is a bottom plan view thereof;

FIG. 7 is a left side elevation thereof; and

FIG. 8 is a right side elevation thereof.
